W. B. Dugan

Attorney

UNITED STATES PATENT OFFICE.

WILLIAM H. MCNEIL, OF HARDY, MISSISSIPPI.

RAIL JOINT.

Application filed September 27, 1922. Serial No. 590,931.

To all whom it may concern:

Be it known that I, WILLIAM H. MCNEIL, a citizen of the United States, residing at Hardy, in the county of Grenada and State 5 of Mississippi, have invented certain new and useful Improvements in Rail Joints, of which the following is a specification.

My said invention relates to a rail joint of improved type and it is an object of the 10 invention to provide a rail joint which shall be firm and substantial and the parts of which shall not be liable to separate accidentally.

Referring to the accompanying drawings, 15 which are made a part hereof and on which similar reference characters indicate similar parts,

Figure 1 is a perspective of the ends of two rails formed according to my invention, 20 and

Figure 2 a vertical section of a rail joint.

In the drawings reference characters 10 and 11 indicate a pair of rails formed at the ends for connection according to my invention. Rail 10 is cut away at one side to remove about one-half of the rail and the web is also cut through at 12 to the opposite side. Rail 11 is similarly cut away but a tongue 13 is left on the second rail, this tongue being adapted to enter and fill the slot 12. Preferably the adjacent sides of the rails are formed somewhat hollow as clearly shown at 14 so that their upper and lower edges may meet before the inner faces come 30 in contact with each other. Transverse holes are formed at 15 in each of the rail sections and bolts 16 are passed through the holes. These bolts are provided with nuts 17 and it will be seen that as the nuts are turned to 35 position the rails may be sprung to a certain extent in drawing them together, thereby giving them a tendency to spring apart and thus effectively locking the nuts in place on the bolts.

It will be seen that by the use of my invention, an effective rail joint is formed in which one rail cannot rise above the other due to the engagement of the tongue 13 with the groove 12. The end of rail 11 abuts directly against the face 18 of the other rail and the end of the rail 10 abuts in similar man-

ner against the separated vertical faces at 19 and 20 on the rail 11. The bolts hold the sections in proper relation and are themselves locked against withdrawal as above 55 explained. The cut away portions at 14 prevent cutting of the bolts due to vibration of the rails, and any weight on the rails, or vibration tending to spread them 60 will act to hold the nuts tight on the bolts. Any slight expansion or "stretch" of the bolts will be taken up by the resiliency of the rails.

My invention is not limited to surface track railings, but may be used on overhead 65 rails or the like and also on girders or other structure where a secure joint is desirable. Various minor changes may also be made in my device without departing from the spirit of the invention, the true scope of which is 70 indicated in the appended claims.

Having thus fully described my said invention, what I claim as new and desire to secure by Letters Patent, is:

1. A rail joint comprising a pair of rails 75 having cut-away portions providing vertical side and end faces, the end and side faces on one rail abutting respectively against those on the other, the web of one rail being cut through to the opposite side and the web 80 of the other rail being formed with a tongue to engage the groove thus formed and means for holding the parts in engaging relation with each other, substantially as set forth.

2. A joint for structural iron or steel comprising a pair of bars having cut-away portions providing vertical side and end faces, the end and side faces on one bar abutting respectively against those on the other, the adjacent side faces being hollowed out to 90 provide for contact at the edges only one of said side faces having a longitudinal slot and the other having a tongue for engagement in the slot and means positioned above the tongue and slot for drawing said faces 95 together against the resilient action of the bars, substantially as set forth.

3. A joint for structural iron or steel, comprising a pair of bars having cut away corners providing vertical end and side faces, 100 the side faces being hollowed out and one of said side faces having a horizontally ex-

tending slot, bolts extending transversely of the bars and positioned between the said slot and the tops of the bars, and nuts on said bolts said nuts being locked by the resiliency 5 of the bars, substantially as set forth.

In witness whereof, I have hereunto set my hand and seal at Memphis, Tennessee,

this 23rd day of September, A. D. nineteen hundred and twenty-two.

WILLIAM H. McNEIL. [L. S.]

Witnesses:

GEO. B. FRAZER,
JOHN W. FARLEY.
